ELEVATOR CONTROL SYSTEM

Anthony Pinto, New Rochelle, and Raymond Alonzo Waite, Yonkers, N. Y., assignors to Otis Elevator Company, New York, N. Y., a corporation of New Jersey

Application May 4, 1935, Serial No. 19,766

25 Claims. (Cl. 172—152)

The invention relates to control systems for elevators.

Various improvements have been made from time to time in the operation of elevators. Among such improvements is the mechanism for bringing the elevator car to an exact level with the desired landing in stopping, regardless of whether the car underruns or overruns the landing, such mechanism usually being referred to as self levelling mechanism. There have been many elevators installed since the advent of self levelling which are not provided with this improvement. Many owners of such installations, as well as of installations made prior to levelling, are desirous of having elevators equipped with levelling apparatus but do not wish for various reasons to install a complete new elevator system. In many of these instances, the elevators are operated on direct current under what is usually termed resistance control, i. e., an installation in which the elevator car is started by connecting the hoisting motor armature to the source in series with resistance and the resistance cut out to bring the car up to full speed, and in which the car is slowed down by including resistance in series with the armature and additional resistance across the armature and cutting this additional resistance out of circuit. It is particularly to such type of control system for elevators that the present invention is applicable although it is useful in connection with certain other arrangements and can be applied to new installations.

The invention involves the provision of self levelling mechanism in resistance control elevator installations.

One feature of the invention is to utilize a direct current generator to supply current at a low voltage to the armature of the hoisting motor of a resistance control installation during the levelling operation.

Another feature is to have the generator in operation prior to the levelling operation but to excite the generator separately excited field winding only for the levelling operation.

Another feature is to utilize a compound wound generator and to render the series field winding of the generator effective during levelling.

Still another feature is to connect the generator armature in the circuit of the hoisting motor armature during full speed operation of the car and for rendering the generator series field winding effective during such full speed operation.

Other features and advantages will become apparent from the specification taken in connection

with the accompanying drawings and the subjoined claims.

The invention may be carried out in various ways. The generator may be driven all the time the elevator car is in service or for less periods as for example only while the car is running. The generator armature may be connected permanently in series with the hoisting motor armature or disconnected at times but connected to the hoisting motor armature for the levelling operation. For the levelling operation, the hoisting motor armature is disconnected from the source and connected across the armature of the generator and the separately excited field winding of the generator is connected to the source to cause the generator to supply current to the hoisting motor armature to bring the car to the floor level.

In the drawings:—

Figure 1 is a schematic wiring diagram of an elevator control system embodying the invention;

Figure 2 is a fragmental schematic wiring diagram of a portion of the elevator system exemplified by Figure 1, illustrating particularly the connections for the generator; and

Figure 3 is a wiring diagram, similar to Figure 2, illustrating variations which may be made in the circuits.

Referring first to Figure 1, certain parts of the elevator control system have been omitted from the wiring diagram in the interest of simplification. This figure is a modified form of "straight" in which the operating connections between the contacts of the switches and their operating magnets are indicated by dot and dash lines. Parts of the system, particularly the coils and contacts of the switches employed therein, may not be in the preferred points in the circuits, certain changes being made in order to make the type of wiring diagram employed as simple as possible.

The elevator hoisting motor has its armature designated 11 and its field winding 12. The hoisting motor is provided with a starting resistance, arranged in steps 13, 14, 15, 16, and 17, and a slow down or by-pass resistance arranged in steps 18, 20, and 21. 22 is a discharge resistance for the hoisting motor field winding while 23 is a resistance for controlling the strength of the hoisting motor field. 24 and 25 are the direct current supply mains for applying power to the hoisting motor under car switch control. 26 is a double pole knife switch for controlling the connection of the system to the supply mains. To suit the type of

diagram employed, the blades of this switch are shown separated.

The driving motor for the generator which applies power to the hoisting motor for the levelling operation has its armature designated 21, its series field winding 28, and its separately excited field winding 30. The armature of the generator is designated 31, its series field winding 32, and its separately excited field winding 33. A resistance 34 is arranged in shunt to the generator series field winding. A resistance 35 is provided for controlling the strength of the generator field. Four additional resistances 36, 37, 38, and 40 are provided for controlling the strength of the generator field. A resistance arranged in steps 44, 45, and 46 is provided for controlling the voltage applied to the armature of the driving motor.

47 and 48 are the up slow speed contacts and the down slow speed contacts respectively of the levelling switch, the levelling switch up and down fast speed contacts being designated 50 and 51 respectively. 52 is the armature and 53 is the field winding of the motor 54 for moving the rollers of the levelling switch into position to clear the levelling cams.

55 is the release coil for the elevator motor electromagnetic brake. This coil is provided with discharge resistances 56 and 57 for controlling the application of the brake during stopping. 58 The car switch is designated as a whole by the numeral 58. 60 is the safety switch in the car. Other safety devices are indicated by legend. 61 is the gate contacts while 62 designates door contacts, only one pair of door contacts being illustrated as indicative of door contacts for each hatchway door, all these door contacts being arranged in series relation.

The electromagnetic switches have been designated as follows:

- 40   A—Auxiliary levelling switch
- B—Brake switch
- C—Speed switch
- D—Down direction switch
- 45   DC—Door contact relay
- DH—Direction holding switch
- DS—Down set-up switch
- E—Speed switch
- F—Field switch
- 50   FR—Series field relay
- G—Speed switch
- H—Accelerating switch
- IR—Inching relay
- J—Accelerating switch
- K—Accelerating switch
- 55   LD—Levelling down direction switch
- LF—Levelling fast speed switch
- LR—Levelling relay
- LS—Load switch
- 60   LU—Levelling up direction switch
- MA—Driving motor accelerating switch
- MS—Driving motor starting switch
- P—Potential switch
- PR—Protective relay
- SF—Series field switch
- SR—Driving motor starting relay
- U—Up direction switch
- US—Up set-up switch

Inductance coils are designated by the character X.

Upon the closing of the knife switch 28, the elevator motor field winding 12 and actuating coil 65 of potential switch P are energized, the circuit for field winding 12 being through resistance 23 and the circuit for coil 65 extending

through contacts 66 of switch P, the various safety devices indicated by legend and including safety switch 60. Potential switch P, upon operation, engages contacts 67, 68, and 70, preparing the control and power circuits. It also separates 5 contacts 66 to insert cooling resistance in circuit with its coil, separates contacts 72 to remove the short-circuit for step 48 of the hoisting motor armature by-pass resistance and engages contacts 69 in the circuit for the brake release coil 55. 10

Assume that the system is arranged for an installation of several floors and that the car is at rest at the first floor landing. In order to start the car in the up direction, the operator moves the car switch into position where its contact bar 15 bridges contacts 76, 77, 78, 79, 80, 81, and 82. Upon contact bar 15 engaging contact 78, a circuit is completed for actuating coil 85 of up direction switch U and actuating coil 86 of brake switch B. This circuit is from supply line 24 20 through the left hand blade of switch 26, by wire 87, through contacts 67 and 70 of switch P, wire 88, by wire 89 through coil 86 of switch B and contacts 90 of speed switch E, wire 91, by wire 92, through coil 85 of switch U, wire 93, contacts 94 25 of direction holding switch DH, car switch contacts 77 and 78, by wire 95, through interlock contacts 96 of down direction switch D, wire 97, contacts 98 of door contact relay DC, door contacts 62, gate contacts 61, lower blade of safety 30 switch 60, wire 100, right hand blade of switch 26, to supply line 25. If either the gate or door is not closed so that the gate contacts 61 or door contacts 62 are separated, the circuit passes through coil 101 of door contact relay DC. This 35 coil is of high resistance, preventing sufficient current being supplied to the coils of switches U and B to effect their operation. This current, however, is sufficient to operate the door contact relay, which separates its contacts 98. This prevents the starting of the car until the door and gate contacts are all closed and the car switch has been returned to neutral to effect the deenergization of coil 101. A circuit is also completed upon contact bar 15 engaging contact 78 for coil 45 102 of levelling relay LR, this circuit extending from the coil to car switch contact 78 through car switch contact 76.

Brake switch B, upon operation, engages contacts 104, completing circuits for the coils 105, 50 106 and 107 of the driving motor starting relay SR, up set-up switch US and down set-up switch DS, respectively. The circuit for coil 105 of the driving motor starting relay is from potential switch contacts 67, wire 87, contacts 104, coil 105 55 of relay SR, inductance coil X108, wire 109, wire 110, wire 111, by wire 112, through potential switch contacts 68, the right hand blade of switch 26, to supply line 25. Coils 106 and 107 of the set-up switches are connected in a circuit parallel 60 to that of coil 105, extending through inductance coil X114. Coils 106 and 107 are holding coils and are not strong enough to effect the operation of their switches.

Coil 105 causes the operation of the driving 65 motor starting relay SR, which engages its contacts 115, completing a circuit for coil 116 of driving motor starting switch MS. This circuit is from wire 88, by wire 117, through contacts 115 and coil 116, wire 118, to wire 112.

The driving motor starting switch MS operates to engage contacts 121, 122, and 123 and to separate contacts 124. The separation of contacts 124 disconnects by-pass resistance 125 from across driving motor armature 27. The engage- 75

ment of contacts 121 and 123 connects the driving motor armature and field winding to the supply lines. The circuit for the armature is from wire 87, by wire 126, through contacts 121, wire 127, through armature 27, series field 28 and resistance steps 46, 45, and 44, by wire 128 through contacts 123, to wire 112. The driving motor separately excited field winding 30 is connected in parallel with the driving motor armature and series field winding and the starting resistance. The completion of these circuits causes the starting of the driving motor and the driving motor accelerating switch MA, coil 130 of which is connected across the motor armature by engagement of contacts 122 of switch MS, operates to engage contacts 131 to short-circuit resistance steps 44, 45, 46 in sequence and finally to short-circuit series field winding 28. This brings the motor-generator set to full speed.

20 Brake switch B, upon operation, also engages contacts 133, 134 and 135 and separates contacts 136. The separation of contacts 136 disconnects discharge resistance 57 from across the brake release coil 55. The engagement of contacts 134 establishes the circuit for brake release coil 55, this circuit being from wire 87 by wire 140 through contacts 134 by wire 141 through brake release coil 55, potential switch contacts 69, brake switch contacts 142, wire 111, to wire 112. Coil 55, upon being energized, acts to release the brake. Contacts 142 separate upon the release of the brake to insert cooling resistance 139 in series with the brake release coil.

Up direction switch U, operating at the same time as brake switch B, engages contacts 148 and 145 and separates contacts 146 and 147. Contacts 147 are interlock contacts and control the connection from supply line 25 to the feed contact 148 of the car switch for downward car travel. Contacts 145, upon engagement, prepare a holding circuit for coil 85 of the up direction switch. The engagement of contacts 144 and separation of contacts 146 connects the armature 11 of the elevator hoisting motor to the supply lines in such way as to cause current to be supplied thereto in a direction to effect upward movement of the elevator car. The circuit for the elevator hoisting motor armature is from potential switch contacts 67, by wire 87 through resistance steps 13, 14, 15, 16, and 17, hold down coil 150 and contacts 151 of down direction switch D, wire 152, contacts 153 of series field switch SF, generator armature 31, hoisting motor armature 11, up direction switch contacts 144, to wire 112.

55 The completion of the circuit for the elevator hoisting motor armature and the release of the brake causes the elevator motor to start the car in the up direction. The engagement of contacts 135 of brake switch B short-circuits resistance 23 in circuit with the elevator motor separately excited field winding 12, bringing the elevator motor field to full strength for the starting operation.

60 The levelling relay LR operates as a result of the completion of the circuit for its coil 102 to engage its contacts 155. This completes a circuit for the levelling switch motor 54, the circuit being from wire 88 by wire 156 through the armature 52 and field winding 53 of the levelling switch motor and contacts 155 of relay LR, wire 157, wire 118, to wire 112. The levelling motor acts to move the levelling switch operating rollers so as to clear the cams during the movement of the car. This operation will be explained later.

75 The engagement of contacts 133 of brake

switch B completes the circuit for coil 160 of speed switch C and for coil 161 of up set-up switch US. This circuit is from wire 88, by wire 162, through contacts 133 of switch B, by wire 163 through coil 160 of switch C, and coil 161 of switch US, to car switch contact 79, this contact being connected by segment 75 to car switch feed contact 78. Up set-up switch US, upon operation, separates contacts 165 and 166 in preparation for the levelling operation. It also engages contacts 167 to complete a circuit for voltage coil 168 of load switch LS. This circuit is from wire 88, wire 170, by wire 171 through contacts 167 of switch US, through coil 168 of switch LS, wire 118, to wire 112. The purpose of the load switch is served during the levelling operation, and will be explained later.

Speed switch C, upon operation, engages contacts 173, 174, and 175 and separates contacts 176. The separation of contacts 176 removes the short-circuit for step 20 of the elevator hoisting motor by-pass resistance and the engagement of contacts 175 short-circuits step 13 of the elevator motor starting resistance. This increases the voltage applied to the elevator motor armature.

The engagement of contacts 174 completes a circuit for coil 179 of the direction holding switch DH, this circuit being from wire 88 by wire 177 through contacts 178 and 180 of the levelling direction switches, inductance coil X181, and coil 179 of direction holding switch DH, contacts 174 of switch C, wire 118, to wire 112. The direction holding switch upon operation, separates contacts 94 and 182 and engages contacts 183 and 184. The engagement of contacts 183 establishes a holding circuit for coil 85 of up direction switch U through contacts 145 of this switch, while the separation of contacts 94 breaks the initial energizing circuit for coil 85. Contacts 182 and 184 serve a similar purpose with respect to the coil of down direction switch D for down car travel.

The engagement of contacts 173 completes a circuit for coil 185 of speed switch E. This circuit is from wire 88, by wire 162 through contacts 133 of switch B, contacts 173 of switch C and coil 185 of switch E to car switch contact 80, this contact being connected by segment 75 to car switch feed contact 78. Switch E, upon operation, engages contacts 186, 187, and 188 and separates contacts 90 and 190. The separation of contacts 90 removes the short-circuit for coil 191 of levelling relay LR. Coil 191 serves as a holding coil for the levelling relay, and its purpose will be explained later. The engagement of contacts 187 completes a circuit for the holding coil 192 of speed switch C, this circuit being from wire 88, wire 193, by wire 194 through coil 192 and contacts 187, wire 195, wire 196, wire 118, to wire 112. The purpose of the holding coil for switch C also will be explained later. The separation of contacts 190 removes the short-circuit for step 21 of the elevator hoisting motor by-pass resistance and the engagement of contacts 188 short-circuits step 16 of the elevator motor starting resistance. This further increases the voltage applied to the elevator motor armature.

The engagement of contacts 186 completes a circuit for coil 197 of speed switch G. This circuit is from wire 88 by wire 162 through contacts 133, by wire 198 through contacts 186 and coil 197, to car switch contact 81, this contact being connected by segment 75 to car switch feed con-

tact 78. Switch G, upon operation, engages contacts 200, 201 and 202 and separates contacts 203. The engagement of contacts 201 completes the circuit for the holding coil 204 of speed switch E, this circuit being from wire 88, wire 193, wire 194, by wire 205 through coil 204 and contacts 201, wire 195, wire 196, wire 118, to wire 112. The purpose of the holding coil for switch E will be explained later. The separation of contacts 203 disconnects the elevator hoisting motor by-pass resistance from across the motor armature. The engagement of contacts 202 prepares a circuit for short-circuiting step 15 of the elevator hoisting motor starting resistance by contacts 206 of accelerating switch H. In the event that, due to load conditions, the elevator hoisting motor does not start upon the release of the brake and the completion of the circuit for the hoisting motor armature by the direction switch, the operation of the speed switches to gradually increase the voltage applied to the motor armature causes the starting of the car.

The engagement of contacts 200 completes the circuit for coil 207 of accelerating switch H. This circuit is from wire 88, by wire 193 through contacts 200, by wire 196 through coil 207, wire 118, to wire 112. Switch H, upon operation, engages contacts 206 and 208. The engagement of contacts 206 short-circuits step 15 of the elevator motor starting resistance, further increasing the voltage applied to the motor armature.

The engagement of contacts 208 completes a circuit for coil 210 of accelerating switch J. This circuit is from wire 88, by wire 193 through contacts 200, by wire 211 through contacts 208 and coil 210, wire 196, wire 118, to wire 112. Switch J, upon operation, engages contacts 212 and 213. The engagement of contacts 212 short-circuits step 16 of the elevator motor starting resistance, further increasing the voltage applied to the motor armature.

The engagement of contacts 213 completes a circuit for coil 214 of accelerating switch K. This circuit is from wire 88, by wire 193 through contacts 200, contacts 213 and coil 214 wire 196, wire 118, to wire 112. Switch K, upon operation, engages contacts 215, 216 and 217. The engagement of contacts 216 establishes a circuit through current coil 219 of load switch LS, contacts 202 and contacts 212, shunting step 17 of the elevator motor starting resistance. Coil 219 being of very low resistance, the engagement of contacts 216 causes the full line voltage to be applied to the motor armature.

The engagement of contacts 217 completes a circuit for coil 218 of field switch F. This circuit is from wire 88, by wire 162 through contacts 133 of switch B by wire 220 through coil 218 and contacts 217 to car switch contact 82, this contact being connected by segment 75 to car switch feed contact 78. Switch F, upon operation, separates contacts 221, removing the short-circuit for resistance 23 for the elevator separately excited field winding, increasing the field strength and bringing the elevator hoisting motor up to full speed.

The engagement of contacts 215 of switch K completes a circuit for coil 222 of series field relay FR. This circuit is from wire 87, by wire 126 through contacts 121, contacts 215, inductance coil X223 and coil 222, by wire 128 through contacts 123, to wire 112. Relay FR, upon operation, engages contacts 224 which completes the circuit for coil 225 of series field switch SF. This circuit is from wire 87, by wire 126 through con-

tacts 121, by wire 228 through contacts 122, by wire 227 through contacts 224 and coil 225, wire 128, to wire 112. The series field switch operates to separate its contacts 153, removing the short-circuit for series field winding 32 of the generator. This renders the generator effective as a series generator in series with the elevator hoisting motor.

This arrangement provides an effective load compensation whereby substantially constant speed is obtained for full speed operation. The generator acts to provide a voltage of proper polarity and of a value which counteracts any tendency of the elevator motor to vary its speed due to load conditions. For example, assume that the elevator motor is lifting a heavy load. This causes positive current of high value to flow in the hoisting motor armature circuit. This current, passing through the series field winding, causes a high excitation of the generator. The generator thus generates a voltage which is added to the voltage applied from the source 24, 25 to the motor. Thus, any tendency of the elevator motor to decrease in speed due to increase in load is effectively counteracted by the generator's applying an additional voltage to the elevator motor to maintain the speed thereof substantially constant. Similarly, should the elevator motor be lowering a heavy load so that the tendency is to overspeed, the generator series field is excited in the opposite direction by the current of negative value which flows in the hoisting motor armature circuit thereby causing the generator to apply a voltage which opposes the line voltage and thereby counteracts the tendency of the hoisting motor to increase in speed.

The amount of compensation provided by the generator is controlled by means of an adjustable resistance 34 connected across the series field winding. The operation of the series field switch to render the generator effective for full speed operation is delayed by means of the inductance coil X223 in series with coil 222 of the series field relay, this inductance delaying the operation of the relay after the application of source voltage to the motor armature and the weakening of the motor field, substantially until the motor comes up to full speed. The generator, with this arrangement, is rendered ineffective during the accelerating period, thereby obviating any undesirable effect due to heavy accelerating currents. This permits a small generator to be used.

To stop the car, the car switch is centered as the car arrives at a predetermined distance from the landing at which it is desired that a stop be made. The centering of the car switch moves segment 75 off contacts 82, 81, 80, 79, 78, and 77. This breaks the circuit for coils 218, 197, 185, 161, 160, and 102 of switches F, G, E, US, C, and LR respectively.

The deenergization of coil 218 of field switch F results in the reengagement of contacts 221 to short-circuit resistance 23 for the elevator motor field winding 12. This causes the car to slow down. The deenergization of coil 197 of speed switch G results in the separation of contacts 202 to reinser resistance steps 15, 16, and 17 in circuit with the elevator motor armature and in the reengagement of contacts 203 to connect steps 18, 20, and 21 of the by-pass resistance across the motor armature. This causes further slow down of the elevator car.

Switch G also separates contacts 200 to deenergize coils 207, 210 and 214 of accelerating switches H, J, and K respectively. The accelerat-

ing switches thereupon drop out to separate contacts 206, 212, and 216, the steps of resistances 15, 16, and 17 respectively controlled by these contacts having already been reinserted in the armature circuit by the separation of contacts 202 of speed switch G. Accelerating switch K also separates contacts 217 in the circuit for coil 218 of field switch F, this circuit having already been broken by the centering of the car switch, and 10 separates contacts 215 to break the circuit for coil 222 of series field relay FR. The series field relay drops out to separate contacts 224, breaking the circuit for coil 225 of series field switch SF. This switch reengages its contacts 153 to short-circuit the series field winding 32 of the generator during the slow down period.

Speed switch E does not drop out immediately the circuit for its coil 185 is broken by the disengagement of car switch segment 75 from contact 80, this switch being maintained operated by its holding coil 204. The circuit for this holding coil is broken by the separation of contacts 201 of switch G. The breaking of this circuit, however, is delayed until after switch G has otherwise performed its functions upon dropping out, this delayed action being indicated by the elongation of the stationary contacting elements of contacts 201. Upon the deenergization of holding coil 204, switch E drops out to separate its contacts 186 in the circuit for coil 191 of switch G, this circuit having already been broken by the centering of the car switch. It also separates contacts 188 to reinsert step 14 of the starting resistance in circuit with the motor armature 35 and reengages contacts 190 to short-circuit step 21 of the by-pass resistance. This causes further slow down of the car.

Switch E also reengages contacts 90 to short-circuit coil 191 of levelling relay LR. Coil 102 of the levelling relay having been deenergized by the centering of the car switch, the relay is maintained operated up to this time by coil 191. The deenergization of coil 191 causes the levelling relay to drop out, separating its contacts 155 and thereby breaking the circuit for levelling switch motor 54. In this manner, the operating rollers of the levelling switch are extended for engagement by the levelling cams. Referring to Figure 2, the levelling switch motor is operatively connected to the levelling switch by means of an arm 230 on the motor shaft, a connecting link 231 and a lever 232. In the starting operation, the motor 54 being energized, arm 230 rotates, acting through link 231 and lever 232 to move the 50 levelling switch as a whole about a pivot. In this manner the levelling switch operating rollers 233 and 234 are moved into position where they do not engage the levelling cams 235 and 236 during motion of the car, a stop being provided to 55 determine the extent of the movement. It is to be understood that levelling cams are provided for each floor. The levelling switch is pivoted on a bracket 237 secured to the car frame. In the 60 stopping operation, upon the deenergization of the levelling switch motor, a spring (not shown) moves the lever 232 and therefore the levelling switch back into the first described position with the rollers 233 and 234 extended for engagement by the levelling cams. Each pair of levelling contacts 47, 48, 50, and 51 comprises a stationary contact and a movable contact operated by the engagement of its corresponding roller and levelling cam. The fast speed contacts 50 and 51 are arranged to separate before their corresponding 65 slow speed contacts 47 and 48 in the levelling op-

eration. Springs (not shown) are provided for causing the separation of the contacts of the pairs as the levelling operation is effected and stops are provided for determining the extent of movement of the rollers as they ride off the levelling cams.

It will be assumed that the car has not reached the landing and that the up levelling switch operating roller 233 has not moved onto the vertical surface of up levelling cam 235 at the time 10 levelling switch motor 54 is deenergized. Switch E, by the delayed opening of its contacts 187, postpones the dropping out of switch C until after switch E has performed its functions in dropping out. The separation of contacts 187 15 breaks the circuit for holding coil 192 of switch C, which drops out to separate its contacts 173, 174, and 175 and to reengage its contacts 176. Contacts 173 are in the circuit for coil 185 of switch E previously broken by the centering of 20 the car switch. The separation of contacts 175 removes the short-circuit for the remainder of the starting resistance for the motor, while the reengagement of contacts 176 short-circuits step 25 20 of the by-pass resistance. This causes further slow down of the elevator car.

The separation of contacts 174 is delayed, as indicated by the elongation of the stationary contacting elements thereof. Upon separation of these contacts, the circuit for coil 179 of direction holding switch DH is broken. Means are provided to delay the dropping out of the holding switch so as to obtain the desired retardation. Inching relay IR has its coil 240 connected across the motor armature and its contacts 241 35 connected in a circuit by-passing coil 179 of switch DH. These contacts are in engagement so that this by-pass circuit is complete at this time. Switch DH is maintained operated by the action of inductance coil X181 in series with coil 40 179 and the resistance connected in this closed circuit. The values of resistance and inductance in this circuit are preferably such that the direction holding switch is maintained operated until the levelling mechanism assumes control. 45

It will be assumed that the up levelling switch operating roller 233 moves onto the vertical surface of up levelling cam 235 before direction holding switch DH drops out. The engagement of levelling switch up slow speed contacts 47 completes a circuit for coil 242 of the levelling up 50 direction switch LU, coil 243 of auxiliary levelling switch AL and coil 244 of brake switch B. This circuit is from wire 88, by wire 245 through coil 244 and coil 243, by wire 246 through coil 242 55 and interlock contacts 247 of levelling down direction switch LD and levelling switch contacts 47, wire 248, wire 157, wire 118, to wire 112. Contacts 250 of protective relay PR in shunt to coil 244 are separated at this time, permitting the 60 energization of this coil by the levelling switch. Coil 251 of the protective relay is connected across the armature 27 of the driving motor of the motor-generator set, the driving motor being in operation, causing the protective relay to be 65 operated condition with contacts 250 separated. The engagement of the levelling switch up fast speed contacts 50 completes a circuit for coil 252 of levelling fast speed switch LF. This circuit is from wire 88, by wire 253 through contacts 254 of driving motor accelerating switch MA (these contacts being closed at the completion of the starting operation for the driving 70 motor of the motor-generator set), coil 252, by 75

wire 255, through contacts 50, wire 256, contacts 47, wire 248, wire 157, wire 118, to wire 112.

The auxiliary levelling switch AL, upon operation, engages contacts 258. The purpose of this switch will be explained later.

The levelling fast speed switch LF, upon operation, engages contacts 259 to short-circuit the portion of resistance 36 employed to cause the levelling operation to take place at slow speed.

10 The levelling up direction switch LU, upon operation, separates contacts 178 and 271 and engages contacts 260, 261 and 262. Contacts 271 are electrical interlocks in the circuit for coil 275 of levelling down direction switch LD. The separation of contacts 178 forces the dropping out of direction holding switch DH to separate its contacts 183. This breaks the circuit for coil 85 of the up direction switch U and coil 86 of brake switch B. The brake switch is maintained operated by its coil 244. The up direction switch, however, drops out, separating its contacts 144 to disconnect the hoisting motor armature from the source. At the same time that the elevator hoisting motor armature is disconnected from the source, the circuit for separately excited field winding 33 of the generator is established by the engagement of contacts 260 and 261 of the levelling up direction switch. The circuit for field winding 33 is from wire 87, wire 263, by wire 264 through contacts 266 of the levelling up direction switch and contacts 268 of down set-up switch DS, by wire 266, through field winding 33 by wire 267, through resistance 48 (contacts 166 being maintained separated by holding coil 166 of up 30 set-up switch US after the deenergization of coil 161 by the centering of the car switch), contacts 261 of the levelling up direction switch, by wire 268 through contacts 268 of levelling fast speed switch, wire 128, to wire 112. Thus, upon the 40 operation of the levelling mechanism to bring the car to the floor landing, the hoisting motor armature is disconnected from the main source of supply and is supplied with current by the generator of the motor-generator set, the armature of the generator and the armature of the hoisting motor being connected in a closed circuit due to the reengagement of contacts 146 of the up direction switch, which by-passes steps 18, 20, and 21 of the by-pass resistance through the 50 hold down coils of the direction switches and contacts 151 of the down direction switch.

With the generator separately excited field winding 33 connected to the source and with contacts 258 of the levelling fast speed switch in engagement, a voltage is generated by the generator which causes the elevator motor to run at a suitable fast levelling speed in the up direction, the brake being maintained released owing to the fact that brake switch B is maintained operated by its coil 244.

Contacts 262 of levelling up direction switch LU are arranged in parallel with contacts 215 of accelerating switch K. The engagement of 65 contacts 262 completes the circuit for coil 222 of series field relay FR. This relay engages contacts 224 to complete the circuit for coil 225 of series field switch SF, which separates its contacts 153 to render the generator series field winding effective for the levelling operation. The operation of the series field relay FR is delayed by inductance coil 223 in order that the current in the generator armature-elevator motor armature circuit may adjust itself to such value that the

proper series field strength for the levelling operation is obtained.

As the car nears the landing, roller 233 rides off the vertical surface onto the oblique surface of cam 235. This results in the separation of up 5 fast speed levelling contacts 50, deenergizing actuating coil 252 of the levelling fast speed relay LF. Relay LF, upon dropping out, separates its contacts 258 to remove the short-circuit for resistance 36. This decreases the voltage applied to separately excited field winding 33 of the generator, decreasing the generator voltage to a value to cause the elevator motor to run at slow levelling speed. Shortly before the car reaches an exact level with the landing, roller 233 rides off the 15 oblique surface of cam 235, thereby separating slow speed levelling contacts 47. This breaks the circuit for coil 243 of auxiliary levelling switch AL, coil 242 of levelling up direction switch LU and coil 244 of brake switch B. The levelling up 20 direction switch operates its contacts 260 and 261 to disconnect the generator separately excited field winding 33 from the source of supply, while brake switch B separates its contacts 134 to deenergize brake release coil 55, applying the 25 brake and bringing the car to a stop. At the same time switch B reengages its contacts 136 to connect discharge resistance 57 in parallel with discharge resistance 58 for the brake release coil 30 for obtaining the desired application of the brake shoes. Switch B also separates contacts 135 to reinsert resistance 23 in the circuit with elevator motor field winding 12, reducing the voltage applied to this winding while the car is at rest. The levelling up direction switch also separates its contacts 262 to deenergize coil 222 of series field relay FR, which in turn separates its contacts 224 to deenergize coil 225 of series field switch SF. The series field switch reengages its contacts 153 to short-circuit generator series field winding 32. 35

Switch B, upon dropping out, also separates contacts 164 to disconnect coil 165 of the driving motor starting relay and holding coil 166 of set-up switch US from the source of supply. These 45 switches do not drop out immediately, however, relay SR being delayed by the effect of inductance coil X108 and discharge resistance 270 and switch US being delayed by the effect of inductance coil X114 and discharge resistance 271. The purpose 50 of the delay in the dropping out of these switches will be seen from later description. Switch US, upon dropping out, separates contacts 167 and 168. The separation of contacts 167 deenergizes coil 168 of load switch LS. 55 The reengagement of contacts 165 and 166 short-circuits levelling control resistances 36 and 48, respectively. Relay SR, upon dropping out, separates contacts 116 to deenergize coil 116 of the driving motor starting switch MS. This 60 switch drops out to separate its contacts 121 and 123, disconnecting the driving motor of the motor-generator set from the source of supply. At the same time, switch MS reengages contacts 124 to disconnect by-pass resistance 125 across the armature 21 of the driving motor, bringing the motor-generator set to a stop. Switch MS also separates contacts 122, disconnecting coil 138 of the driving motor accelerating switch MA across the driving motor armature 21. This switch drops out, separating its contacts 131 and 254 in preparation for the next operation. 65

In the event of overrun, assuming in the above example that the car overruns the floor to the extent of causing the engagement of down slow 70 75

speed levelling contacts 48, a circuit is completed for coil 215 of the levelling down direction switch. This circuit may be traced from wire 88, by wire 245 through coil 244 of switch B and coil 5 243 of switch AL, by wire 276, through interlock contacts 277 of levelling up direction switch LU, coil 275, contacts 48, wire 248, wire 157, wire 118, to wire 112.

The brake switch B engages its contacts 104, 10 reestablishing the circuit for the coils 105 and 106 of driving motor starting relay SR and up set-up switch US, respectively. As previously explained, these switches are maintained operated after contacts 104 disconnect their coils from their 15 source of supply by the action of their respective inductance coils and discharge resistance. This portion of the system is adjusted so as to maintain these switches in operated condition during an overrun until the circuit for their coils is again 20 established as a result of the engagement of the slow speed levelling switch contacts for returning the car to the floor, these contacts being levelling down direction switch contacts 48 in the example assumed. Thus, upon an overrun, relay SR is 25 maintained operated, maintaining the driving motor for the motor-generator set in operation. Also, up set-up switch US is maintained operated with its contacts 165 and 166 separated.

The levelling down direction switch LD, upon 30 operation, engages its contacts 280 and 281, completing a circuit for the generator separately excited field winding 33. This circuit may be traced from wire 87, wire 263, by wire 282, through contacts 280, by wire 283 through resistance 36 35 (contacts 165 being maintained separated by the up set-up switch as above explained), by wire 266, through field winding 33, contacts 284 of down set-up switch DS and contacts 281, by wire 268 through resistance 35, wire 128, to wire 112. Due 40 to the reversal of the flow of current through field winding 33 from that during levelling with the car approaching the floor in the up direction, the car is caused to start in the down direction, the brake being lifted as a result of the engagement 45 of contacts 134 of brake switch B. Since levelling fast speed switch LF is not operated, resistance 35 is included in the circuit, causing the voltage generated by the generator to be such as to cause the hoisting motor to operate the car at slow 50 levelling speed.

The levelling down direction switch LD also 55 engages contacts 285 to complete a circuit for the coil 222 of the series field relay FR, contacts 285 being arranged in parallel with contacts 262 of levelling up direction switch LU. The series field relay causes the operation of the series field switch SF as before to remove the short-circuit for the generator series field winding 32. This operation 60 is delayed by the action of inductance coil X223, to insure that the current in the generator armature-motor armature circuit has fallen to a low value before the series field winding is rendered effective.

65 As the car returns to the floor, it is stopped by the separation of levelling switch slow speed contacts 48 in a manner similar to that for approaching a floor in the up direction. If the overrun is great enough to cause the engagement of 70 levelling switch down fast speed contacts 51 as well as contacts 48, coil 252 of the levelling fast speed switch LF is energized. As before, switch LF engages contacts 258, causing the voltage generated to be of a value to cause the elevator motor 75 to run at its fast levelling speed. Shortly after

the car is returned to the floor, the driving motor starting relay SR drops out, causing the discontinuance of the operation of the motor generator set.

The starting of the car in the down direction is 5 accomplished in a manner similar to that for starting the car in the up direction, and will be described only briefly. The operator moves the car switch into position where segment 75 bridges contacts 286, 287, 148, 289, 290, 291, and 292. 10 The bridging of contacts 148 and 287 completes a circuit for coil 86 of brake switch B and coil 293 of down direction switch D. This circuit may be traced from wire 87, by wire 89, through coil 86 of brake switch B and contacts 90 of switch E, 15 wire 91, by wire 294 through coil 293 of switch D, contacts 182 of switch DH, contacts 287 and 148 of the car switch, by wire 295 through interlock contacts 147 of switch U, to supply line 25 as traced for coil 85 of switch U. The circuit for coil 20 102 of levelling relay LR is by way of contacts 286 of the car switch. The circuit for coil 160 of speed switch C is by wire 296 through coil 297 of down set-up switch DS. The circuit for coil 185 of speed switch E is by way of car switch contact 290 25 and wire 279. The circuit for coil 197 of speed switch G is by way of car switch contact 291 and wire 298. The circuit for coil 218 of field switch F is by way of car switch contact 292 and wire 300. The down direction switch D, upon 30 operation, engages contacts 301 and 302 and separates contacts 151 and 96. The engagement of contacts 302 prepares the holding circuit for coil 293 of switch D, which is later completed by the engagement of contacts 184 of switch DH. The 35 engagement of contacts 301 and the separation of contacts 151 completes the circuit for the armature of the elevator hoisting motor for operating the car in the down direction. The down set-up switch DS separates contacts 265 and 284. 40 Further than this, the operation of starting the car in the down direction is the same as for starting the car in the up direction. The slowing down and stopping of the car during its downward travel is similar to that described for the slow down and 45 stopping of the car during its upward travel. Such operation will not be described as it is believed that it will be understood from previous description.

Load conditions have not been considered in the 50 description of operation up to this point. Means are provided which are effective during levelling to compensate for the load on the hoisting motor. This compensation is effected by means of load switch LS acting on resistance in circuit with generator field winding 33. The load switch is provided with a current coil 219 and a voltage coil 168. The voltage coil is ineffective to cause operation of the load switch but acts to maintain the switch, once operated, in operated condition. 60 The current coil is rendered effective during acceleration upon the operation of the last accelerating switch K. With this arrangement, the load switch operates when the current which flows in the current coil at the time that coil is 65 rendered effective is at or above a predetermined value.

It will be assumed that the switch is adjusted to operate at balanced load, it being understood that the exact point at which the switch operates is 70 determined by the characteristics of the particular installation. Upon operation of the switch, it separates contacts 305 and 306 and engages contacts 307 and 308, these contacts controlling resistances 36, 37, 38, and 41. The set-up switches 75

US and DS control the effectiveness of the load switch contacts in accordance with the direction of car travel. Also, the up set-up switch, by its contacts 167, maintains the load switch, if operated, in operated condition upon an overrun during upward car travel. Similarly, down set-up switch contacts 310 maintain the load switch, if operated, in operated condition upon an overrun during downward car travel. Thus load switch contacts 305 and 306 are separated while load switch contacts 307 and 308 are engaged. Also, contacts 165 and 166 of the up set-up switch US are separated due to the fact that the car is travelling in the up direction. Under such conditions, the generator field winding circuit for the up levelling operation does not include resistance 37 and includes only a portion of resistance 40 as resistance 37 is short-circuited by contacts 265 of the down set-up switch DS and all but a portion of resistance 40 is short-circuited by load switch contacts 308. This gives the desired higher value of generated E. M. F. for lifting the car and its load up to the floor.

If, under the conditions above assumed, the car overruns the floor, resistance 36 is included in the circuit with field winding 33 for the return operation because load switch contacts 305 and up set-up switch contacts 165 are separated, thereby giving a lower value of generated E. M. F. to compensate for the load on the elevator motor now being an overhauling one, i. e., the car and its load overbalancing the counterweight.

If the car had been running in an up direction lightly loaded so that the load switch is not operated, the load is an overhauling one (the car being overbalanced by the counterweight) so that, with load switch contacts 308 separated, resistance 40 is included in the generator field winding circuit to provide a lower value of generated E. M. F. In case of an overrun under such conditions, it becomes necessary to lift a load (the counterweight) to return the car to the floor so that, load switch contacts 305 being in engagement, only a small portion of resistance 36 is included in the generator field winding circuit, thereby giving a higher value of generated E. M. F. to compensate for the load.

The action is similar for downward car travel. Assume that the car is travelling downwardly lightly loaded, which means that the elevator motor is lifting a load. Contacts 265 and 284 of down set-up switch DS are separated because the car is travelling downwardly, while contacts 305 and 306 of the load switch are separated and contacts 307 and 308 of the load switch are engaged, owing to the fact that the motor is lifting a load. Thus, during underrun conditions, only a small portion of resistance 38 is included in the generator field winding circuit to give a higher value of generated E. M. F. and during underrun conditions all of resistance 37 is included in the field winding circuit to give a lower value of generated E. M. F. because the load for returning the car to the floor is an overhauling one. In case the car is heavily loaded during its downward travel, the elevator motor is lowering a load, so that the load switch is not operated. Therefore all of resistance 38 is included in the field winding circuit during underrun conditions while only a portion of resistance 37 is included in this circuit during overrun conditions.

Should the car, while standing at a floor, be moved downwardly from the floor into the levelling zone, as by the taking on of a heavy load, the protective relay PR acts to prevent the lift-

ing of the brake to move the car until the motor-generator set has been started and has come up to a predetermined speed. The coil 251 of the protective relay is connected across the driving motor armature 27 so as to be subject to the counter E. M. F. of the driving motor and therefore the speed of the motor-generator set. Contacts 250 of the protective relay are connected in shunt to coil 244 of the brake switch B. Thus, coil 244 cannot be energized by the levelling mechanism to operate the brake switch and thus to effect the release of the brake until the driving motor has come up to a certain speed. Additional contacts 254 on driving motor accelerating switch MA serve a similar purpose. These contacts prevent the operation of the levelling fast speed switch LF to place a load on the generator by short-circuiting resistance 35 under such conditions, in the event the car sags into the fast speed levelling zone, until the motor-generator set comes up to a predetermined speed, the coil 130 of this switch being subject to the armature 27 of the driving motor of the set. The auxiliary levelling switch AL acts under such conditions to effect the starting of the motor-generator set. The coil 243 of this switch is connected in a circuit common to the coils of the levelling direction switches so as to operate the switch when either one of the levelling direction switches operates. Contacts 259 of the auxiliary levelling switch are connected in parallel with contacts 104 of the brake switch to cause the operation of the driving motor starting relay SR and thus the starting of the motor-generator set when the operation of the brake switch is prevented due to coil 244 being short-circuited by contacts 250. Thus, should the car, while standing at a floor, sag into the levelling zone, the motor-armature set is started by the action of switch AL but the operation of bringing the car back to the floor and the placing of any considerable load on the generator are delayed until the motor-generator set attains a predetermined speed.

Should any of the safety devices operate or should the safety switch 60 in the car be operated, the potential switch A is deenergized. This switch, in dropping out, breaks the control circuits, causing the car to be brought to a quick stop. Involved in this emergency stopping operation is the separation of contacts 69 of switch A to prevent the connecting of resistance 57 across the brake coil, giving a hard braking action, and the engagement of contacts 72 of switch A to connect a small portion of by-pass resistance across the hoisting motor armature, resistance steps 18, 20, and 21 being excluded from the by-pass circuit.

The inching relay IR, having its operating coil 240 connected across the elevator motor armature 11 and its contacts 241 in the by-pass circuit for coil 179 of the direction holding switch DH, acts to prevent the direction holding switch being held in by the effect of inductance coil X181 unless the elevator motor is up to a certain speed. This permits the attendant in the car to inch the car without having to wait on any time elements in the event that he throws his car switch too far over in performing the inching operation.

Many of the control operations previously described are in the nature of refinements, and may be varied or omitted entirely. Also, the manner of effecting other control operations may be modified. The motor-generator set has been described as starting up with the starting of the

elevator car and stopping when the elevator car is brought to an exact landing level. Other arrangements may be employed, as, for example, having the motor-generator set run all the time 5 the elevator car is in service, the arrangement shown in Figure 1 being principally for conserving power.

In Figure 2, simplified circuits are shown for illustrating the principles of operation of applicants' invention as exemplified by Figure 1. The manner of starting and stopping the car is not shown as this may be accomplished in several ways. The contacts of direction switches, however, are shown, these being designated 144, 146, 151, and 301 to correspond with the designations of such contacts in Figure 1. These contacts are operated in accordance with the direction of car travel desired, as, for example, by the manipulation of a car switch or the pressing of a push 20 button, to complete a circuit for the armature 11 of the elevator hoisting motor. The armature 31 of the generator of the motor-generator set is included in this circuit and may be driven only while the elevator motor is in operation or all 25 the time the elevator is in service or for other periods, as, for example, by maintaining the set in operation for a predetermined time interval after the car is stopped. The switch B for controlling the electromagnetic brake BR is illustrated 30 as having a coil controlled by the levelling mechanism. The other coil of the switch may be energized in any suitable manner in starting, depending upon the installation. No control is illustrated for field winding 12 of the hoisting motor, as this may be arranged to suit the requirements of the particular installation. If desired, a full field may be maintained on the hoisting motor so long as the elevator car is in 35 service.

In starting the car, the circuit for the brake release coil is completed by the engagement of contacts 134 of brake switch B, releasing the 40 brake. The circuit for the hoisting motor armature 11 is completed by the operation of the direction switch, the circuit including generator armature 31 and starting resistance SR in series with the motor armature with by-pass resistance BP connected across these armatures. The by-pass resistance is increased during acceleration 45 and finally disconnected and the starting resistance is short-circuited in steps and finally the armatures of the hoisting motor and generator are connected directly to the source, bringing the 50 hoisting motor up to full speed.

When the car is to stop at a landing, starting resistance SR is reinserted in circuit with the elevator motor armature 11 and generator armature 31 and by-pass resistance BP is reconnected 55 across these armatures and short-circuited. When the levelling mechanism takes control, the elevator motor armature 11 is disconnected from the source of supply and connected in a local circuit with armature 31 of the generator through contacts 146 and 151 of the direction switches. As this takes place, the levelling mechanism completes the circuit for the generator field winding 60 65 70 75 75 to render the generator effective to apply voltage to the elevator motor to bring the car to the landing level. The generator series field winding 32 is rendered effective for the levelling operation by the operation of switch SF so as to compensate for load. When the car comes to an exact landing level, generator field winding 33 is

disconnected from the source and the brake is applied to bring the car to a stop.

The series field winding 32 of the generator may be controlled so as to be rendered effective during full speed operation of the elevator motor 5 as well as during levelling. With the series field rendered effective for full speed operation, the generator acts to compensate for load so as to provide substantially the same speed of the elevator car, regardless of load. By using a generator of 10 the proper size and characteristics, the series field winding may be left in during the acceleration and retardation periods. In such case, the generator would act as an accentuator in that during acceleration it would act to increase the voltage 15 applied to the elevator motor armature as the speed in acceleration steps takes place, due to the increased current flow each time the voltage applied to the elevator motor armature is increased.

Any suitable arrangement for controlling the 20 circuit for the separately excited field winding 33 of the generator for levelling may be employed. This includes not only the circuits but also the levelling mechanism itself. Other forms of levelling mechanism than that diagrammatically 25 illustrated in this figure may be employed, a diagrammatic illustration of one form of levelling control mechanism being made in this figure for convenience.

The levelling mechanism is illustrated as acting 30 through levelling direction switches LU and LD for controlling the circuits for generator field winding 33 and as acting through brake switch B to control the action of the elevator hoisting 35 motor brake. In the arrangement shown, the levelling mechanism acts through levelling fast speed switch LF and resistance 35 to control the voltage applied to the field winding 33. The mechanism for causing fast speed operation during levelling may be omitted, if desired, thereby 40 providing single speed levelling operation.

Certain of the variations which may be made are embodied in the wiring diagram of Figure 3. As in the case of Figure 2, the circuits of Figure 3 are simplified for illustrating the principles of 45 operation. The manner of starting and stopping the car is not shown. The contacts of the direction switches are designated 144, 146, 151, and 301 as before. The direction switches may be provided with a walking beam to serve as a mechanical interlock, in which event the back contacts of both direction switches cannot be closed at the same time. Such arrangement is assumed and only contacts 151 are shown closed, on the assumption that the car has been travelling in the 50 up direction. The armature 31 of the generator of the motor-generator set is not arranged in the hoisting motor armature circuit. Instead it is located in the circuit for the by-pass resistance BP. 60 The starting resistance is arranged in two parts. The starting resistance SSR controlled by the speed switches is arranged in the armature circuit inside the direction switch contacts, while the resistance ASR controlled by the accelerating 65 switches is arranged in the armature circuit outside the direction switch contacts. This arrangement, as well as the arrangement of Figures 1 and 2, is found in many existing elevator installations.

The brake BR is released in starting the car by the completion of the circuit for the brake release coil by the engagement of contacts of a switch operated in the starting operation, these contacts being designated 315. At starting, by-pass re- 70 75

distance BP and generator armature 31 are connected across the armature 11 of the hoisting motor and starting resistances SSR and ASR are connected in series therewith. The by-pass resistance is increased during acceleration of the hoisting motor. Disconnection of the by-pass resistance also disconnects generator armature 31 from across the hoisting motor armature. The series resistances SSR and ASR are decreased during acceleration and finally armature 11 of the hoisting motor is connected directly to the source of power. This brings the elevator car up to full speed.

In slowing down and stopping the car at a landing, starting resistance ASR is reinserted in circuit with the elevator motor armature 11 and then starting resistance SSR is reinserted in the motor armature circuit. The by-pass resistance BP and the generator armature 31 are connected across the motor armature at the time starting resistance SSR is reinserted in circuit, and the value of the by-pass resistance is decreased as the short-circuit for the steps of starting resistance SSR is removed. When the levelling mechanism takes control, the elevator motor armature is disconnected from the source of supply and connected in the local circuit with armature 31 of the generator through contacts 316, closed in response to the operating of the levelling mechanism. The levelling mechanism also causes the closure of contacts 317, which by-pass contacts 315 to maintain the brake release coil energized and the brake released. As this takes place, the levelling mechanism completes the circuit for the generator field winding 33 to render the generator effective to apply voltage to the elevator motor to bring the car to the landing level. The generator series field winding 32 is rendered effective to compensate for load during levelling by the operation of switch SF. When the car comes to an exact landing level, generator field winding 33 is disconnected from the source and the brake is applied to bring the car to a stop.

The contacts 47, 48, 50, and 51 of the levelling switching mechanism are illustrated as acting through electromagnetic switches LB, LU, LD, and LF to control the levelling of the car, contacts 316 and 317 being provided on switch LB.

The arrangement of the generator armature in the by-pass circuit has the advantage that the armature is not subjected to the peaks of starting current and therefore a smaller generator may be employed. However, this arrangement lacks the advantage of the generator providing load compensation for full speed operation, as with the generator armature arranged in series with the motor armature as in the case of Figures 1 and 2. In case of change-over installations, the character of the installation may determine the point where the generator armature is placed in the circuits.

Circuits are also shown in Figure 3 for controlling the starting and stopping of the driving motor for the motor-generator set. In the arrangement shown, the motor-generator set is arranged so that it may be maintained in operation all the time the car is in service, a manual switch SS being arranged in the control circuits for the driving motor to start and stop the driving motor at will.

The switch SS comprises a bridge member 320 which, when turned counterclockwise, bridges contacts 321 to complete a circuit for coil 322 of driving motor starting switch MS. This switch

engages contacts 323 and 324. The engagement of contacts 323 completes the circuit for the armature 27 and separately excited field winding 30 of the driving motor. The engagement of contacts 324 connects coil 325 of driving motor accelerating switch MA across armature 27 of the driving motor. When the voltage of the driving motor rises to a predetermined point, switch MA operates to engage contacts 326 and 327. Contacts 321 short-circuit resistance in series with the driving motor armature, applying full line voltage to the driving motor to bring it to full speed. Contacts 326 establish a circuit for coil 322 of driving motor starting switch MS, bypassing contacts 321 and bridge member 320. The starting switch may thereupon be released and is returned to the position shown as by a spring. In this position, bridge 328 remains in contact with contacts 330. To stop the driving motor, switch SS is turned counterclockwise, moving bridge 328 into position where it disengages contacts 330. This breaks the circuit for coil 322 of switch MS and switch MS drops out, disconnecting the driving motor from the source of supply. The driving motor starting switch MS is illustrated as provided with an additional pair of contacts 331 arranged to short-circuit the generator armature and series field winding when the motor-generator set is not in operation. This may be provided on installations where it may be desired to operate the elevator car at times without the levelling control.

The invention is particularly applicable for changing over existing "resistance control" installations, i. e., elevator installations in which the elevator motor is controlled by resistance in series with the motor armature and resistance connected in the by-pass circuit for the motor armature. Such installations may be changed over to embody the invention in a very simple manner by the addition of the small motor-generator set and suitable mechanism for controlling the operation of this set.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. In a control system for an elevator car in which the car is started by connecting the hoisting motor for the car to a source of direct current with resistance in series with the motor armature and accelerated by cutting this resistance out of circuit, and in which the car is retarded by including resistance in series with said armature and connecting resistance in parallel with said armature, a direct current generator, means for driving the generator, means for causing said driving means to drive said generator at least while the car is in operation, means for connecting the field winding of said generator to said source, levelling mechanism, means for disconnecting said hoisting motor armature from said source and connecting it across the armature of said generator to cause said generator armature to supply current to the hoisting motor armature for the operation of bringing the car to an exact landing level under the control of said levelling mechanism, and means responsive to the operation of said levelling mechanism for disconnecting said field winding from said

source when the car becomes level with the landing.

2. In a control system for an elevator car in which the car is started by connecting the hoisting motor for the car to a source of direct current with resistance in series with the motor armature and accelerated by cutting this resistance out of circuit, and in which the car is retarded by including resistance in series with said armature and connecting resistance in parallel with said armature, a direct current generator, driving means for the generator, means for causing said generator to be driven by said driving means at least all the time the car is running, levelling mechanism, means for disconnecting said hoisting motor armature from said source, means for connecting said armature across the armature of said generator, and means for connecting the field winding of said generator to said source to cause said generator armature to supply current to the hoisting motor armature for the operation of bringing the car to an exact landing level under the control of said levelling mechanism.

3. In a control system for an elevator car in which the car is started by connecting the hoisting motor for the car to a source of direct current with resistance in series with the motor armature and accelerated by cutting this resistance out of circuit, and in which the car is retarded by reincluding said resistance in series with said armature and connecting resistance in parallel with said armature, a direct current generator, driving means for the generator, means for causing operation of said driving means to drive said generator all the time the car is in service, levelling mechanism, and means responsive to the operation of said levelling mechanism for disconnecting said hoisting motor armature from said source, for connecting the armature of said hoisting motor across the armature of said generator and for connecting the field winding of said generator to said source to cause said generator armature to supply current to the hoisting motor armature for the operation of bringing the car to an exact landing level under the control of said levelling mechanism.

4. In a control system for an elevator car in which the car is started by connecting the hoisting motor for the car to a source of direct current with resistance in series with the motor armature and accelerated by cutting this resistance out of circuit, and in which the car is retarded by including resistance in series with said armature and connecting resistance in parallel with said armature, a direct current generator, a driving motor for the generator, a manually operable switch, means responsive to the operation of said switch for connecting said driving motor to said source to drive said generator, levelling mechanism, means for completing a local circuit including the armature of said generator and the armature of said hoisting motor in series relation, and means for disconnecting said hoisting motor armature from said source and for connecting the field winding of said generator to said source to cause said generator to supply current to the hoisting motor for the operation of bringing the car to an exact landing level under the control of said levelling mechanism.

5. In a control system for an elevator car in which the car is started by connecting the hoisting motor for the car to a source of direct current with resistance in series with the motor armature and accelerated by short-circuiting this resistance in steps, and in which the car is retarded by

reincluding said resistance in series with said armature and connecting additional resistance in parallel with said armature and decreasing the amount of said additional resistance in steps; a direct current generator, the armature of said generator being connected in series relation with the hoisting motor armature; a motor for driving said generator; and means for causing said hoisting motor to level the car with the landing at which a stop is being made, said means comprising levelling mechanism, means for connecting the armature of said generator and the armature of said hoisting motor in a local circuit, means for disconnecting said hoisting motor armature from said source and means responsive to the operation of said levelling mechanism for connecting the field winding of said generator to said source to cause said generator armature to supply current to the hoisting motor armature for the operation of bringing the car to an exact landing level under the control of said levelling mechanism.

6. In a control system for an elevator car in which the car is started by connecting the hoisting motor for the car to a source of direct current with resistance in series with the motor armature and accelerated by short-circuiting this resistance in steps, and in which the car is retarded by reincluding said resistance in series with said armature and connecting additional resistance in parallel with said armature and decreasing the amount of said additional resistance in steps, a direct current compound wound generator, the armature of said generator being connected in series relation with the hoisting motor armature; a motor for driving said generator; means for causing said hoisting motor to level the car with the landing at which a stop is being made, said means comprising levelling mechanism, means for connecting the armature of said generator and the armature of said hoisting motor in series relation in a local circuit, means for disconnecting said hoisting motor armature from said source, and means responsive to the operation of said levelling mechanism for connecting the field winding of said generator adapted for separate excitation to said source to cause said generator armature to supply current to the hoisting motor armature for the operation of bringing the car to an exact landing level under the control of said levelling mechanism; means for controlling the effectiveness of the series field winding of said generator; and means for causing operation of said controlling means to render said series field winding effective during levelling.

7. In a control system for an elevator car in which the car is started by connecting the hoisting motor for the car to a source of direct current with resistance in series with the motor armature and accelerated by short-circuiting this resistance in steps, and in which the car is retarded by reincluding said resistance in series with said armature and connecting additional resistance in parallel with said armature and decreasing the amount of said additional resistance in steps; a direct current compound wound generator, the armature of said generator being connected in series relation with the hoisting motor armature; a motor for driving said generator; means for causing said hoisting motor to level the car with the landing at which a stop is being made, said means comprising levelling mechanism, means for connecting the armature of said generator and the armature of said hoisting motor in series relation in a local circuit, means for dis-

connecting said hoisting motor armature from said source and means responsive to the operation of said levelling mechanism for connecting the field winding of said generator adapted for separate excitation to said source to cause said generator armature to supply current to the hoisting motor armature for the operation of bringing the car to an exact landing level under the control of said levelling mechanism; and means for rendering the series field winding of said generator ineffective except during levelling and full speed operation of said hoisting motor.

8. In a control system for an elevator car in which the car is started by connecting the hoisting motor for the car to a source of direct current with resistance in series with the motor armature and accelerated by short-circuiting this resistance in steps, and in which the car is retarded by reincluding said resistance in series with said armature and connecting additional resistance in parallel with said armature and decreasing the amount of said additional resistance in steps; a direct current compound wound generator, the armature of said generator being connected in series relation with said additional resistance so as to be connected across the hoisting motor armature along with said additional resistance; a motor for driving said generator; means for causing said hoisting motor to level the car with the landing at which a stop is being made, said means comprising levelling mechanism, means for excluding said additional resistance from the parallel circuit for the hoisting motor armature thereby connecting the armature of said generator and the armature of said hoisting motor directly in series in a local circuit, means for disconnecting said hoisting motor armature from said source and means responsive to the operation of said levelling mechanism for connecting the field winding of said generator adapted for separate excitation to said source to cause said generator armature to supply current to the hoisting motor armature for the operation of bringing the car to an exact landing level under the control of said levelling mechanism; and means for rendering the series field winding of said generator ineffective except during levelling.

9. In a control system for an elevator car; a source of direct current; a direct current hoisting motor for the car; a direct current generator; driving means for the generator; means for causing operation of said driving means to drive said generator so long as the elevator car is in service; means for causing current to be supplied to said hoisting motor from said source for full speed operation of the car; means for causing said hoisting motor to level the car with a desired landing in stopping; and means for causing current to be supplied to said hoisting motor by said generator at a low voltage for the levelling operation.

10. In a control system for an elevator car; a source of direct current; a direct current hoisting motor for the car; a direct current generator having a separately excited field winding; driving means for the generator; means for causing operation of said driving means to drive said generator at least when the elevator car is running; means for connecting the armature of said hoisting motor to said source in series with resistance to start the car; means for cutting out said resistance to bring the car up to full speed; means for including resistance in series with said armature and for connecting additional resistance in parallel with said armature to slow down the

car; and means for causing said hoisting motor to level the car with a desired landing in stopping, said levelling means comprising means for connecting said field winding of said generator to said source and means for disconnecting the hoisting motor armature from said source and connecting it across the armature of said generator to cause said generator armature to supply current to the hoisting motor armature for the levelling operation.

11. In a control system for an elevator car; a source of direct current; a direct current hoisting motor for the car; a starting resistance for said motor; a direct current generator; driving means for the generator; means for causing operation of said driving means to drive said generator so long as the elevator car is in service; means for connecting the armature of said hoisting motor to said source in series with said starting resistance to start the car; means for cutting out said starting resistance to bring the car up to full speed; means for reincluding said starting resistance in series with said armature and for connecting said by-pass resistance in parallel with said armature to slow down the car; and means for causing said hoisting motor to level the car with a desired landing in stopping, said levelling means comprising levelling switching mechanism, and means responsive to the operation of said levelling switching mechanism for connecting the field winding of said generator to said source, for disconnecting the hoisting motor armature from said source and for connecting the armature of said generator directly across the armature of said hoisting motor to cause said generator armature to supply current to the hoisting motor armature for the operation of bringing the car to an exact landing level under the control of said levelling switching mechanism.

12. In a control system for an elevator car; a source of direct current; a direct current hoisting motor for the car; a starting resistance for said motor; a by-pass resistance for said motor; a direct current generator, the armature of which is connected permanently in series relation with the armature of said hoisting motor; driving means for the generator; means for connecting the armature of said hoisting motor to said source in series with said starting resistance to start the car; means for cutting out said starting resistance to bring the car up to full speed; means for reincluding said starting resistance in series with said armatures and for connecting said by-pass resistance in parallel with both armatures to slow down the car; and means for causing said hoisting motor to level the car with a desired landing in stopping, said levelling means comprising, levelling switching mechanism, and means responsive to the operation of said levelling switching mechanism for connecting the field winding of said generator to said source, for disconnecting the hoisting motor armature from said source and for connecting the armature of said generator directly across the armature of said hoisting motor to cause said generator armature to supply current to the hoisting motor armature for the operation of bringing the car to an exact landing level under the control of said levelling switching mechanism.

13. In a control system for an elevator car; a source of direct current; a direct current hoisting motor for the car; a starting resistance for said motor; a by-pass resistance for said motor; a direct current generator, the armature of which

- is connected permanently in series relation with the armature of said hoisting motor; driving means for the generator; means for connecting the armature of said hoisting motor, with said by-pass resistance in parallel with both armatures, to said source in series with said starting resistance to start the car; switching means for disconnecting said by-pass resistance from across said armatures and for cutting out said starting resistance to bring the car up to full speed and for reincluding said starting resistance in series with said armatures and reconnecting said by-pass resistance in parallel with said armatures to slow down the car; and means for causing said hoisting motor to level the car with a desired landing in stopping; said levelling means comprising means for connecting the armature of said generator directly across the armature of said hoisting motor and for disconnecting the hoisting motor armature from said source, levelling switching mechanism and means responsive to the operation of said levelling switching mechanism for connecting the field winding of said generator to said source to cause said generator armature to supply current to the hoisting motor armature for the operation of bringing the car to an exact landing level under the control of said levelling switching mechanism.
14. In a control system for an elevator car; a source of direct current; a direct current hoisting motor for the car; a starting resistance for said motor; a by-pass resistance for said motor; a direct current compound wound generator, the armature of which is permanently connected in series relation with the armature of said hoisting motor; driving means for the generator; means for connecting the armature of said hoisting motor, with the armature of said generator in series therewith and with said by-pass resistance in parallel with both armatures, to said source in series with said starting resistance to start the car; switching means for disconnecting said by-pass resistance from across said armatures and for short-circuiting said starting resistance to connect said hoisting motor armature in series with said generator armature directly to said source to bring the car up to full speed and for reincluding said starting resistance in series with said armatures and reconnecting said by-pass resistance in parallel with said armatures to slow down the car; means for causing said hoisting motor to level the car with a desired landing in stopping, said levelling means comprising means for short-circuiting all of said by-pass resistance to form a local circuit for the armature of said generator and the armature of said hoisting motor, means for disconnecting the armature of the hoisting motor from said source, levelling switching mechanism and means responsive to the operation of said levelling switching mechanism for connecting the generator separately excited field winding to said source, such field winding not being energized except during levelling, to cause said generator armature to supply current to the hoisting motor armature for the operation of bringing the car to an exact landing level under the control of said levelling switching mechanism; and means for rendering the series field winding of said generator ineffective except during levelling and full speed operation of said hoisting motor.
15. In a control system for an elevator car; a source of direct current; a direct current hoisting motor for the car; a direct current compound wound generator; driving means for the gen-
- erator; means for connecting the armature of said hoisting motor to said source in series with resistance to start the car; means for cutting said resistance out of circuit to bring the car up to full speed; means for connecting resistance in parallel with said armature to slow down the car; means for disconnecting the hoisting motor armature from said source; means for connecting the armature of said hoisting motor across the armature of said generator; means for energizing the generator separately excited field winding; means for causing said hoisting motor to level the car with a desired landing in stopping with current supplied to the hoisting motor by the generator, said levelling means causing the supply of current from the generator to the motor to be discontinued when the car becomes level with the landing; and means for rendering the series field winding of said generator effective during the levelling operation.
16. In a control system for an elevator car; a source of direct current; a direct current hoisting motor for the car; a direct current compound wound generator; driving means for the generator; means for connecting the armature of said hoisting motor with the armature of said generator in series therewith to said source in series with resistance to start the car; switching means for cutting said resistance out of circuit to bring the car up to full speed and for including resistance in series with said armatures and additional resistance in parallel with said armatures to slow down the car; means for causing said hoisting motor to level the car with a desired landing in stopping, said levelling means comprising means for disconnecting the hoisting motor from said source and for connecting it to the armature of said generator and means for connecting the generator separately excited field winding to said source to cause said generator armature to supply current to the hoisting motor armature for the levelling operation; and means for rendering the series field winding of said generator effective only during levelling and full speed operation of said hoisting motor.
17. In a control system for an elevator car; a source of direct current; a direct current hoisting motor for the car; a starting resistance for said motor; a by-pass resistance for said motor; a direct current compound wound generator; driving means for the generator; means for connecting the armature of said hoisting motor with the armature of said generator in series therewith and said by-pass resistance in parallel with both armatures to said source in series with said starting resistance to start the car; switching means for disconnecting said by-pass resistance from across said armatures and for short-circuiting said starting resistance to connect said hoisting motor armature in series with said generator armature directly to said source to bring the car up to full speed and for reincluding said starting resistance in series with said armatures and reconnecting said by-pass resistance in parallel with said armatures to slow down the car; means for causing said hoisting motor to level the car with a desired landing in stopping, said levelling means comprising means for disconnecting the hoisting motor from said source and for short-circuiting all of said by-pass resistance to form a local circuit for the armature of said generator and the armature of said hoisting motor, and means for connecting the generator separately excited field winding to said source to cause said generator armature to supply current to the hoisting motor

- armature for the levelling operation; and means for rendering the series field winding of said generator ineffective except during levelling and full speed operation of said hoisting motor.
- 5 18. In a control system for an elevator car; a source of direct current; a direct current hoisting motor for the car; a direct current generator having a separately excited field winding; driving means for the generator; means for connecting the armature of said hoisting motor to said source in series with resistance to start the car and for cutting out said resistance to bring the car up to full speed; means for including resistance in series with said hoisting motor armature and resistance across said hoisting motor armature to slow down the car, the armature of said generator being connected in series with the last mentioned resistance across the hoisting motor armature; and means for causing said hoisting motor to level 10 the car with a desired landing in stopping, said levelling means comprising means for connecting the generator separately excited field winding to said source and for disconnecting the hoisting motor from said source and cutting said last mentioned resistance out of circuit.
- 15 19. In a control system for an elevator car; a source of direct current; a direct current hoisting motor for the car; a direct current generator having a separately excited field winding; driving means for the generator; resistance; means for connecting the armature of said hoisting motor to said source in series with said resistance to start the car; switching means for cutting said resistance out of circuit to bring the car up to full speed; additional resistance; means for reincorporating the first mentioned resistance in series with said hoisting motor armature and for connecting said additional resistance across said hoisting motor armature to slow down the car, the armature of said generator being included in the circuit for said additional resistance across the hoisting motor armature in series relation with said additional resistance; and means for causing said hoisting motor to level the car with a desired landing in stopping, said levelling means comprising means for disconnecting the hoisting motor from said source and for connecting the armature of said generator directly across the armature of said hoisting motor, and means for connecting the generator separately excited field winding to said source to cause said generator armature to supply current to the hoisting motor armature for the operation of bringing the car to an exact landing level.
- 20 20. In a control system for an elevator car; a source of direct current; a direct current hoisting motor for the car; a starting resistance for said motor; a by-pass resistance for said motor; a direct current compound wound generator, the armature of which is connected in series relation with said by-pass resistance; driving means for the generator; means for connecting the armature of said hoisting motor, with the armature of said generator and said by-pass resistance in series connected in parallel thereto, to said source in series with said starting resistance to start the car; switching means for disconnecting said by-pass resistance and generator armature from across said hoisting motor armature and for short-circuiting said starting resistance to con-

nect said hoisting motor armature directly to said source to bring the car up to full speed and for reincorporating said starting resistance in series with said hoisting motor armature and reconnecting said by-pass resistance across said hoisting motor armature to slow down the car, said generator armature being reconnected in series with said by-pass resistance across the hoisting motor armature; means for causing said hoisting motor to level the car with a desired landing in stopping, said levelling means comprising means for short-circuiting all of said by-pass resistance to form a local circuit for the armature of said generator and the armature of said hoisting motor, means for disconnecting the hoisting motor from said source, levelling switching mechanism and means responsive to the operation of said levelling switching mechanism for connecting the generator separately excited field winding to said source, such field winding not being energized except during levelling, to cause said generator armature to supply current to the hoisting motor armature for the operation of bringing the car to an exact landing level under the control of said levelling switching mechanism; and means for rendering the series field winding of said generator effective only during the levelling of said car.

21. In combination, a motor of the direct current, rheostatic control type having resistances in series and in parallel with the armature for speed control, connections driving the motor from line current at normal speed, a relatively small low voltage generator in series with the motor, and connections operating the motor solely by current from said generator at low speeds.

22. In combination, a main motor, means for connecting the motor to power lines, a generator having its armature permanently in series with the motor, a circuit for connecting the field of the generator with power lines, and automatic means opening said circuit when the motor is connected to the power lines.

23. In elevator operating apparatus, a motor, means to connect the motor to power lines for normal operation, an auxiliary generator permanently in series with the motor and having a field, leveling switches, and means controlled by the leveling switches for energizing the field in the direction necessary to supply current in proper direction to the motor for leveling action and with said motor disconnected from the power lines.

24. In combination, an electric motor, means to connect the motor with power lines for normal operation, a relatively small generator permanently connected with the motor circuit, said generator having a shunt field, and means to energize said field, only while said motor is disconnected from said power lines, for low speed operation of the motor.

25. In an elevator operating apparatus, a motor, power lines, connections from the power lines to the motor for normal operation of the motor at high speed and low speed, a relatively small generator having its armature permanently included in said connections, and means for driving the motor solely by current from the generator for leveling operations.

ANTHONY PINTO.
